UNITED STATES PATENT OFFICE.

AMBROSE CALIVER, OF NASHVILLE, TENNESSEE.

WORK CABINET.

Application filed November 30, 1923. Serial No. 677,796.

To all whom it may concern:

Be it known that I, AMBROSE CALIVER, a citizen of the United States, residing at Nashville, in the county of Davidson, State of Tennessee, have invented certain new and useful Improvements in Work Cabinets, of which the following is a specification.

My invention relates to improvements in work cabinets, and consists in the combinations, constructions, and arrangements herein described and claimed.

An object of the invention is to provide a cabinet of simplified construction which affords facilities when in open position for supporting in conveniently and easily accessible positions all the necessary articles of equipment and supplies required by a hair dresser or beauty culturist to enable her to perform the duties incident to her occupation without discomfort to either the customer or the worker.

A further object of the invention is to provide a device of the character described which when in closed position has the appearance of an article of furniture, being adapted by its construction to have any desirable finish and general design to match other articles of furniture as desired.

A further object of the invention is to provide a device of the character described which may be constructed in such manner as to be either portable or stationary as desired.

A still further object of the invention is to provide a device of the character described which includes comfortable seats for the support of both the customer and the worker while the worker serves the customer, whereby the worker may perform her work conveniently and easily with but relatively little fatigue.

Other objects and advantages will be apparent from the foregoing description considered in conjunction with the accompanying drawings, in which:

Figure 1 is a perspective view showing the cabinet embodying the invention in closed position,

Figure 2 is a vertical section along the line 2-2 of Figure 1 showing also in dotted lines the position of a seat for the customer when the seat has been extended,

Figure 3 is a view similar to Figure 1

showing the cabinet with parts thereof opened out,

Figure 4 is a fragmentary sectional view illustrating the manner of supporting a mirror for use,

Figure 5 is a perspective view of a removable shelf comprised in the device,

Figure 6 is a fragmentary sectional view showing a modified form of cabinet,

Figure 7 is a view similar to Figure 2 showing another modification,

Figure 8 is a fragmentary perspective view showing a slideable seat supporting member and the means whereby it may be supported at its outer end,

Figure 9 is a fragmentary perspective view showing a portion of the structure exhibited in Fig. 7, and

Figure 10 is a fragmentary perspective view showing still other portions of the structure exhibited in Fig. 7.

In carrying out my invention I provide a cabinet case having parallel sides 1 and 2, respectively, a bottom 3, and a back 4, all secured together in any suitable known manner. The bottom 3 may be provided with legs 5 supported on casters 6, whereby the device may be conveniently moved along a supporting floor or like supporting surface, such as that indicated at 7 in Figure 2. The cabinet case is provided with vertical partition 8 which divides the interior of the case into a relatively large compartment 9 located between the partition 8 and the side wall 2 and a smaller space located between the partition 8 and the side wall 2, the last named space being closed at the front by a fixed front wall 10 which may be formed with a plurality of vertically spaced openings indicated respectively at 11, 12 and 13.

In the embodiment of the invention illustrated, drawers 14 and 15, respectively, are mounted to slide in openings 11 and 12, respectively, and the opening 13 normally

is closed by a swinging door 16. The space between the partition 8 and the side 2 is closed at its upper end by a section 17 of the top of the cabinet case. The section 17 is fixed in place in any suitable known manner. A swingable section 18, which together with the section 17, constitutes the top of the cabinet case, is hinged at 19 to the fixed section 18 and is swingable from the position shown in Figure 3 to the position shown in

Figure 1, in which latter position the section 18 closes the compartment 9 at the upper end of the latter.

The compartment 9 is closed at its front by a door 20 which together with the fixed front wall 10 constitutes the front of the cabinet case. The door 20 may be held in open position as shown in Figure 3 by a removable shelf or work-supporting member 21 which is provided with pins 22 extending laterally from one face thereof, certain of the pins engaging vertical openings 23 in the upper end of the door 20 while the remaining pins 22 engage with vertical openings 24 in the upper end of the side 1, whereby the shelf or work-supporting member 21 is held against displacement from the side 1 and door 20 and the door 20 also is releasably held against movement from open position.

20 A panel 25 is mounted at its lower end, as at 26, upon the bottom of the compartment 9 to swing about a horizontal axis from inactive position, as shown in Figure 2, to active position, as shown in Figure 3. It will be observed that the panel 25 is provided on the face thereof which is lowermost when the panel is in active position with spaced apart bars or supports 26 which co-operate with a portion of the bottom wall of the compartment to support the panel 25 substantially in a horizontal position and in a plane parallel with the bottom 3 when the panel 25 has been swung outwardly and downwardly to active position. When the panel 25 is in inactive position it is substantially vertically disposed and both the panel and supporting members 27 are completely housed within the compartment 9.

40 A seat 28 is carried by the panel 25 and is positioned above the panel when the latter is in outwardly swung or active position and inwardly within the compartment 9 from the panel 25 when the latter is in substantially vertical position. The seat 28 may be supported upon the panel 25 in any suitable manner, preferably through the agency of a standard 29 which is adjustable as to length and comprises a lower or socket section 29^a and an upper screw section 29^b which is mounted to turn in the bore of the socket member 29^a. The standard 29 has a flanged or laterally enlarged base portion 29^c which is in sliding engagement with and retained by a dove-tailed mortise 30 in a block 31 which is attached to the panel 25, the mortise 30 constituting a guide slot along which the standard 29 may be moved bodily to adjust the position of the seat 28 upon the panel 25 to vary the distance within the limits set by the length of the slot between the seat 28 and the space within the compartment 9.

60 A substantially horizontal supporting plate-like member 32 is disposed within the compartment 9 adjacent to but spaced from the upper end of the latter, the supporting

member 32 preferably being of sufficient width to be secured at its side edges to the side 1 and the partition 8, respectively, and of sufficient length to be secured at its rear edge to the back 4 and to terminate at its front edge in a plane located at an appreciable distance from the plane of the front edges of the side 1 and partition 8, whereby a space is provided between the front edge of the supporting member 32 and the door 20 for the accommodation of the panel 25 when the latter is in inactive position and the door 20 is closed. The supporting member 32 constitutes a combined shelf and seat as will presently appear. This supporting member also serves to support a mirror 33 which may be lowered through a slot 34 in the rear part of the plate 32 to hang suspended from the plate 32 as shown in Figure 2, being prevented from moving completely through the slot 34 by a lateral projection 35 at the upper end of the mirror. A pair of swinging retaining arms 36 are pivoted at their upper ends to the mirror at opposite sides of the latter, as at 37, and terminate at their lower ends below the plane of the lower end of the mirror, being provided at their lower ends with laterally turned portions 38 which are adapted to engage with the lower face of the plate 32 when the mirror has been raised to prevent the mirror from being removed bodily from the plate 32 from the position shown in Fig. 3. In the last-named position the mirror 33 rests at its lower end upon the upper face of the plate 32 and is tilted to contact at its back with the vertically extending upper end portion of the back of the cabinet case.

From the foregoing description of the various parts of the device the operation thereof may be readily understood. The drawers 14, 15 may receive the supplies and articles which are required by the worker in performing the duties of her occupation. Also certain articles of the usual equipment of the hair dresser or beauty culturist may be placed within the lower part of the space between the partition 8 and the side 2, which space is accessible when the door 16 has been opened. A towel rack 39 may be secured to the inner face of the door 20. When the door 20 has been opened, the panel 25 may be swung outwardly to the position shown in Figure 3. As stated, the seat 28 preferably is supported on the panel 25 by a mounting of the swivel and vertically adjustable type of construction. The seat 28 is adjusted initially if desired so that the customer seated thereon may bend over the supporting member 32. A removable basin (not shown) may be placed upon the shelf 32 for holding the cleansing liquid in which the hair of the customer is washed. The seat 28 then is revolved until the customer

faces the direction opposite to the shelf 32 and when the basin has been removed from the shelf 32, the latter constitutes a seat for the worker who is then in position not only 5 to treat the customer but to conveniently grasp any desired tool or article of supply which may be disposed on the open cover section 18, in either of the drawers 14 and 15 or the compartment back of the door 10 16, or on the removable shelf 21 which has previously been removed from the lower part of the compartment 9 and has been placed in the position shown in Figure 3.

It, therefore, will be apparent that the 15 work incident to the operation of treating the hair of a customer or of performing the usual operations incident to the practice of beauty culture may be performed with ease and comfort both to the customer and to 20 the worker and without the usual delay occasioned by the movement of the worker from place to place to secure the various articles which may be required during different steps of the work.

25 It will be obvious that the mirror 33 may be secured to the device by means other than that illustrated without departing from the spirit and scope of the invention. For example, the mirror 33 may be housed 30 within the space provided within the compartment 9 above the supporting member 32. Also a basin such as that indicated at 50 in Figure 6 may be a fixed part of the supporting member 32 and may be provided 35 with a drain pipe 51 which may lead to any desirable place. For example, if the device is stationary, the drain pipe 51 may lead to the waste pipe of the usual water supply system.

40 In the form of the device illustrated in Figure 7, the horizontal supporting plate 32 is formed with a relatively large opening therein in which is received a basin 60 having an outwardly extending flange at its 45 upper end overlying the portion of the plate 32 which margins the opening therein. A cover 61 for the basin is shown as being a plate hinged at its rearward edge at 62 to the supporting plate 32. The cover 61 may 50 be swung upwardly and rearwardly to the inclined position shown in Figure 10 in which it rests against the extending upper end portion of the back 4. A mirror 63 may be secured to the cover 61 against the 55 face thereof which is lowermost when the cover is in downwardly swung position, the mirror being secured to the cover in any suitable known manner, as for instance, by the retaining strips 64.

60 The block 31 in which the base of the seat-carrying standard 29 slides may be secured to a horizontal base or supporting plate 65 in superimposed relation to the latter. The base 65 is adapted to be slid 65 in its plane until completely disposed with-

in the compartment 9 as shown by the full lines in Fig. 7 or until extended from the compartment 9 at the front of the cabinet as indicated by the dotted lines in Fig. 7. The slideable movement of the base 65 70 which preferably slides upon the bottom 3 is limited through the agency of laterally extending pins 66 at the side edges of the base 65 working in slots 67 in guiding and retaining bars 68 which are secured within 75 the compartment 9 at opposite sides of the base 65. Only one of the guiding and retaining bars 68 is shown and, therefore, only one of the pins 66 is shown (see, Fig. 9), but it is thought that the construction 80 which includes a pair of bars 68 and two of the pins 66, respectively disposed at opposite sides of the base 65 will be understood. Pins 69 driven through each bar 68 and through the horizontal slot 67 may have 85 the dual function of securing the bars 68 to the bottom 3 and of providing stops for engaging with one of the pins 66 to limit the slideable movement of the base 65.

The base 65 is provided with a laterally elongated supporting leg 70 which is hinged thereto by a three-piece or triple leaf hinge, such as that indicated at 71, so that the leg may swing downwardly and inwardly from the full line position shown in Figure 7 90 when the base is in extended position to the dotted line position of Figure 7. In the latter named position, the leg 70 is in abutting relation at its upper end to the under-face of the base 65 adjacent to the outer end of the latter, while in the full line position, the leg 70 lies in a plane of the base 65 and may be retracted with the latter within the compartment 9. The supporting leg 70 may be provided with end section, such as that indicated at 73 in Fig. 8, hinged to the supporting leg to swing about a vertical axis when the leg is in downwardly swung position to the position shown by the full lines in Fig. 8. In this position, the end section 73 serves as a brace 100 between the supporting leg 70 and the base 65.

The operation of the form of the device exhibited in Figure 10 is identical in essential respects with the operation of the device shown in Figures 1 and 2. When the cover 61 is in downwardly swung position, it may serve as a seat for the worker or as a support for various articles which the worker uses from time to time. It is to be observed that the seat 28 ordinarily would be swung through 180° from the position illustrated in Figure 7 when the base 65 is in extended position and the device is in use but, of course, the seat 28 will be returned to the position indicated by the full lines when the base 65 is slid to position within the compartment 9.

Obviously, my invention is susceptible of 120

embodiment in forms other than those illustrated in the drawings and I, therefore, consider as my own all modifications and adaptations thereof which fairly fall within 5 the scope of the appended claims.

I claim:

1. A device of the character described comprising a case having a compartment open at the front and at its upper end, a 10 panel supported upon the bottom wall of the compartment for movement to and from position within the compartment, a seat supported on said panel in position to be disposed upright, a substantially horizontal 15 supporting member disposed in the upper part of said compartment, said supporting member constituting a combined shelf and second seat, and a swinging cover section for closing the compartment at its upper 20 end, said cover section being adapted to be swung from position to close said compartment to horizontal position at one side of the compartment to support articles in position conveniently accessible to a person 25 who is seated on said second named seat.

2. A device of the character described comprising a case having a compartment open at the front and at its upper end, a

panel supported on the bottom wall of the compartment for movement to and from 30 position within the compartment, a seat supported on said panel in position to be disposed upright, a substantially horizontal supporting member disposed in the upper part of said compartment, said supporting member constituting a combined shelf and second seat, a swinging cover for 35 closing the compartment at its upper end, a door for closing the compartment at the front of the latter, and a removable shelf 40 adapted to be supported upon the door and the adjacent portion of the case, said removable shelf and said door and adjacent portion of the case having co-operative means for holding the removable shelf 45 against displacement and for holding the door in open position, said cover being swingable from compartment-closing position to substantially horizontal position on the base at the side of the compartment opposite to said removable shelf and to then be adapted to support articles in positions 50 conveniently accessible to a person who is seated on said second named seat.

AMBROSE CALIVER.
